TOBACCO CURING APPARATUS

William Turner Wagoner, Elon College, N. C.

Application October 1, 1946, Serial No. 700,476

3 Claims. (Cl. 237—53)

1

This invention relates to the curing of tobacco and more particularly to the combination of a drying house and an associated heating system for subjecting uncured green tobacco to the proper temperatures during the curing process.

In the production of flue-cured tobacco, the green uncured tobacco is gathered from the field and suspended within a house where it is subjected to a curing process incurring temperatures ranging upwardly from 85 degrees to 200 degrees Fahrenheit over a period of approximately 100 hours. If high quality tobacco is to be produced, it is very important that the temperatures be carefully maintained within certain prescribed limits during each stage of the curing process in accordance with the response of the particular type of tobacco to heat. If, for example, a bright leaf tobacco is being cured, either an excess or deficiency of heat for a substantial period during the early stages of the process will result in a darkened or discolored cured product.

Heretofore, various heating systems, such as furnaces, oil burning units, and combinations of furnaces and oil burning units, have been employed in association with drying houses for effecting the above named process. These systems have been objectionable, due to the lack of economy or difficulty in operation, or both. In view of the high temperatures prevailing within the house during certain curing stages, it is very desirable to locate the source of heat on the exterior to avoid the necessity of exposing the attendant to high temperatures for comparatively long periods when regulating the heat. It is equally important that a maximum amount of the heat produced on the exterior be conveyed without loss to the tobacco on the interior of the house. Where furnaces alone or a combination of furnaces and oil burners are employed, the drying house floor absorbs a large portion of the heat produced, thereby impairing the efficiency.

It is an object of this invention to provide a tobacco curing apparatus which will obviate the above-mentioned problems encountered with prior devices of this character.

It is another object of this invention to provide a tobacco curing apparatus wherein the combustion chamber of a heating unit extends inwardly through a wall of the associated drying house in spaced relation to the floor of the latter to prevent an excessive amount of heat radiation from the chamber to said floor.

It is another object of this invention to provide a tobacco curing apparatus of the character described in which a heating element, such as an

2

oil burner, is located in that portion of the combustion chamber disposed on the exterior of the house, and in which a flue system is connected to the inner end of the chamber whereby the heat is uniformly distributed over the bottom area of the house and below the tobacco suspended from above.

It is still another object of this invention to provide a heating unit for a drying house, comprising a hollow elongated frusto-conical combustion chamber having the larger end thereof disposed on the exterior and the smaller end disposed on the interior of the house, said larger exterior end being provided with a heating means, and the wall thickness of said chamber progressively decreasing in thickness with the increase in distance of any portion of the wall from the heating means.

Some of the objects of the invention having been stated, other objects will appear as the description proceeds when taken in connection with the accompanying drawings, in which:

Figure 1 is an isometric view of a drying house and associated heating system employed for curing tobacco;

Figure 2 is a sectional plan view taken through the lower portion of Figure 1;

Figure 3 is a cross-sectional detail view taken along the line 3—3 in Figure 1, illustrating the means for varying the air draft in the heating system;

Figure 4 is a vertical sectional detail view taken along the line 4—4 in Figure 2, showing the relative positions of the heating system and the suspended tobacco within the drying house;

Figure 5 is an enlarged vertical sectional view taken along the line 5—5 in Figure 2, illustrating structural details of the combustion chamber and the associated heating means;

Figure 6 is a sectional detail view taken along the lines 6—6 in Figures 2 and 5;

Figure 7 is a sectional plan view taken along the line 7—7 in Figure 6, illustrating the means for vertically adjusting the position of the heating means with relation to the combustion chamber, and

Figure 8 is an exploded isometric view of the combustion chamber and portions of the heating means.

Referring more particularly to the drawings, the numeral 10 broadly designates a drying house, which house comprises side walls 11 and 12, front wall 13, rear wall 15, floor 16, and roof 17, the side wall 11 being provided with a door 18. Suitable horizontally disposed tier poles 19 are supported

by side walls 11 and 12 approximately seven feet above the floor 16, and these poles in turn are adapted to support a number of sticks or holders 20 having uncured tobacco plant leaves 21 suspended thereon in the proper position to be subjected to the curing process.

As previously stated, the curing of bright leaves is usually completed within about 100 hours after the green leaves are gathered from the field, and hence the application of heat is necessary. Also, the skill with which the attendant maintains the proper amount of heat during the various stages of the curing process determines to a large degree the final color and quality of the cured tobacco. Furthermore, the ability of the attendant to properly regulate the heat is dependent upon the sensitivity and efficiency of the curing apparatus, which in the present instance is the combination of a drying house and a heating system.

Accordingly, a pair of horizontally disposed frusto-conical combustion chambers 26 and 26' have been mounted in the front wall 14 of the drying house 10 in spaced relation to floor 16. It will be observed that both of these chambers and their associated heating and fuel supply means are substantially identical. Therefore, only the chamber 26 and associated heating and fuel supply means will be described, and like reference characters with prime notations added will be applied to corresponding parts of chamber 26' and its associated structure.

The larger end of frusto-conical chamber 26 projects a short distance beyond the exterior surface of the wall 14, whereas the smaller end projects into the drying house a somewhat greater distance beyond the inner surface of this same wall. Chamber 26 comprises an outer metallic frusto-conical casing 27 which is lined with a suitable heat resistant material 28 such as fire clay. The outer end of metallic casing 27 is provided with a lug 29 fitting into a slot 30 of an inspection door 31, which door is likewise provided with a lining 32 of fire clay or other suitable material. In order to maintain the door 31 in closed position, suitable bolts 33 project from the enlarged end of the combustion chamber and are adapted to penetrate holes in the door 31 when the latter is closed. Wing nuts 34 on the projecting portions of bolts 33 serve to clamp the door in closed position. A handle 31a is provided so that door 31 can be swung about hinge point 29, 30 from bold line to dotted line position, as shown in Figure 5 after the wing nuts 34 are removed from bolts 33, thereby providing access to the interior of the chamber from the exterior of the drying house.

By observing Figures 5 and 8 it will be seen that the lower wall portion at larger end of chamber 26 has an opening 35 therein disposed adjacent the inspection door 31. A heating means is mounted for vertical adjustment within opening 35, said heating means preferably comprising an oil burner; however, it is evident that other sources of heat may be employed. This heating means comprises a heat retaining plate 37 having an outside size and shape substantially conforming to opening 35, but somewhat smaller so as to provide operating clearances 38. The central portion of plate 37 has a rectangular opening 39 therein, said plate being adapted to rest upon the upturned flanges of channel member 40 so that opening 39 will be centrally positioned with respect to burner cup 41 mounted upon the channel web therebelow. The upper rim portion of

cup 41 is positioned immediately below the level of the lower surface of the plate 37.

A U-shaped oil supply pipe 45 is provided with vertical leg portions 45a and 45b, the leg 45b leading downwardly from the central interior portion of cup 41, and through the web of channel member 40. Leg 45b is adjustably clamped in fixed position to a stake 46 by means of hook bolts 47, said bolts penetrating the stake and having wing nuts 48 threadably secured on the projecting ends (Fig. 7). By manipulating wing nuts 48, the pipe 45 and the associated burner structure designated by reference characters 37, 40 and 41 may be adjusted vertically in the desired positions to thereby properly space the burner with respect to the ceiling of the combustion chamber and the opening 35.

The upper end of leg 45b is connected to a regulating valve 50, and leading from this valve 20 is a comparatively flexible supply pipe 51, the other end of the latter pipe being connected at 52 to a third supply pipe 53 (Figs. 1 and 2). Pipe 53 communicates with the interior of oil supply tank 54, and has a shut-off valve 55 therein.

From the foregoing description it is apparent that the valve 50 is employed to vary the flow of oil from supply tank 54 to the burner cup 41, and hence the heat generated will vary accordingly. If the flow of oil should be sufficient to overflow the rim of cup 41, at least a portion of the excess will be retained on the web of channel member 40 by means of beads 40a and 40b where the surface area of the flame will be enlarged. Should the oil also overflow the beads 35 40a and 40b, the latter overflow will drop into pit 57, and when ignited will serve to preheat the oil passing through U-shaped supply pipe 45, as well as to supplement the heat produced by the burner thereabove.

Leading from the smaller inner end of combustion chamber 26 in parallel relationship to side and back walls 12 and 15 is an L-shaped flue pipe 58. At a point approximately at the mid portion of the back wall, the pipe 58 is connected to a pipe 59 which projects forwardly and slightly upwardly to a point outside the front wall 14. The projecting end of pipe 58 communicates with the lower end of a smoke stack 60, said stack extending upwardly to a point above the house roof 17.

In order to vary the draft produced by the flue system and stack 60 a suitable draft regulator is provided, comprising a cylindrical band 61 having an opening 61a therein. Band 61 is rotatably mounted around the stack and has a handle 61b by means of which the band is rotated (Figs. 1 and 3). When the opening 61a in the band is brought into coincidence with the opening 60a in the stack, the draft in the flue system is correspondingly diminished.

Particular attention is invited to the manner of positioning chamber 26 in wall 14. It will be noted that the longitudinal axis of the chamber is inclined slightly upwardly as the latter extends 65 into the drying house, thereby causing the uppermost interior portion of the chamber to be substantially horizontal whereas the bottom inside portion is inclined to a greater extent than the longitudinal axis. Such an arrangement permits the heat produced at the burner to readily flow into the flue pipe system, and also facilitates the removal of ashes, soot and the like from the chamber when the inspection door 31 is opened.

The frusto-conical streamlined shape of the combustion chamber is designed with a view of

offering a minimum resistance to the flow of the heat currents within the chamber from the exterior to the interior of the drying house. At the point where the flame is generated the heat intensity is greater, and hence there is a greater necessity for more space, as well as for a thicker fire clay lining 26. At points more remote from the flame, the intensity of the heat decreases; consequently, the thickness of the fire clay and the cross-sectional area of the chamber are correspondingly reduced. Such a construction permits substantially uniform heat radiation over the entire length of the chamber to the interior of the house. When an excess of heat is permitted to radiate from an area of a tobacco curing flue system, the tobacco suspended directly thereabove is also subjected to an excess of heat, resulting in scorching and damage to the cured tobacco.

In the drawings and specification there have been set forth a preferred embodiment of the invention, and although specific terms have been employed they are used in a generic sense and not for purposes of limitation, the scope of the invention being set forth in the following claims.

I claim:

1. In a tobacco curing apparatus, the combination of a substantially horizontally disposed elongated hollow member having the entire inner and outer wall surfaces thereof respectively concentric about and uniformly convergent toward a common longitudinal axis from one end to the other of said member, the pitch of said inner convergent surface being less than that of said outer convergent surface with respect to said axis to thereby define a wall of progressively decreasing thickness from said first-named end to said other end of the member, means providing an opening in the lower portion of said wall and at the first-named larger end of said member, an

oil burner vertically positioned within said opening along an axis disposed substantially at right angles to said concentric axis, and an access door for normally closing the first-named larger end of said hollow member.

5 2. Tobacco curing apparatus as defined in claim 1 wherein said inner and outer surfaces of the elongated hollow member are each frustoconically shaped, and wherein said access door, when closed, comprises one side of said opening.

10 3. Tobacco curing apparatus as defined in claim 1, further comprising a drying house, one wall of said house supporting the larger and smaller ends of said horizontally disposed elongated member in cantilevered positions respectively on the exterior and interior of said house, whereby clear space is provided beneath said exteriorly located larger end for manipulation of the burner and whereby clear space is also provided beneath the interiorly located smaller end to retard heat conduction to the drying house floor.
